FILING CABINET, LOCK, AND TRAY

Stanley B. Freiberg, Cincinnati, Ohio

Application February 25, 1929. Serial No. 342,645

2 Claims. (Cl. 45—94)

This invention relates to improvements in a filing device.

An object of the invention is to provide an improved filing cabinet and means for locking trays 5 therein.

Another object is to provide a lock for filing cabinets which is simple, positive and capable of being actuated by a single operation.

Another object is to provide such a lock means 10 which can be used equally well in cabinets containing few or many trays, and which is equally effective with trays or drawers of varying sizes and depths.

Another object is to provide such a locking device which can be controlled by standard types 15 of lock and key.

Another object is to provide an improved means for supporting shelves within a cabinet.

These objects are attained by the means de- 20 scribed herein and set forth in the accompanying drawings, in which:

Fig. 1 is a perspective view of the cabinet of the present invention with the lock and shelf-support means installed therein, parts being broken away.

Fig. 2 is a front elevational view of the cabinet and lock means, parts being broken away.

Fig. 3 is a view taken on line 3—3 of Fig. 2.

Fig. 4 is a view taken on line 4—4 of Fig. 2, 30 parts being broken away.

Fig. 5 is a detail view of elements of the lock means.

Fig. 6 is an isometric detail view showing that 35 element of the lock means by which the trays are engaged by the lock.

Fig. 7 is an isometric view showing the development of a shelf member of this invention.

Fig. 8 is an end view of the shelf mounting.

The filing tray and its guide shown herein are 40 set forth in detail in my copending application Serial No. 325,589, filed December 12, 1928.

The cabinet structure illustrated in connection with the present invention is of the type set forth 45 in my copending application Serial Number 436, 366, filed March 17, 1930.

With reference now to the drawings; the cabinet 50 12 comprises the side walls 13 and 14, top 15, the raised bottom 16 and rear wall 17, the latter and the corners adjacent thereto being suitably strengthened as indicated in Fig. 3. The panels 18, 19 and 20 bordering the front of the cabinet are preferably formed by turning in portions of the sides and top respectively. Portions 21 and 22, which may be integral with panels 18 and 19 55 respectively, are formed into vertical channels

23 and 24, opening to the interior of the cabinet. Portions 21 and 22 are cut off immediately above the raised bottom 16, which extends forwardly to abut the inner sides of panels 18 and 19, thus closing the channels 23 and 24 at the lower ends 60 thereof. A base panel 25 extends between panels 18 and 19 the upper edge of panel 25 abutting bottom 16 as indicated at 26 (Fig. 1).

The mountings 27, of this invention are individual members resembling channel bars and extending longitudinally of the cabinet in abutment with the inner faces of side walls 13 and 14. Mountings 27 are preferably formed of metal sheets or blanks 28 which are provided at each end with the extensions 29, 30 and 31. Blank 28 65 is bent, as indicated by dotted lines in Fig. 7, so as to provide a shelf member comprising an upper ledge 32, a secondary ledge 33 and bottom 34. Extensions 29 and 31 are now in spaced alignment and project from ledge 32 and bottom 70 34 respectively. The shaped extensions 30 are bent inwardly of the mountings, so that the top edges of extensions 30 fall immediately beneath the end edges of ledges 32 and 33, and the bottom edge of extensions 30, immediately above the end 75 edge of bottom 34.

The shelves 35 are substantially flat sheets of a width slightly less than the inside width of cabinet 12, and of proper length to permit their insertion between rear wall 17 and the innermost projections of portions 21 and 22. Each shelf 35 is adapted to be supported on each side by one of the mountings 27.

The mountings and shelves are positioned 90 within the cabinet by a building-up process. Initially, two of the mountings 27 are oppositely disposed along the walls 13 and 14, the bottoms 34 of the mountings resting upon the raised bottom 16 of the cabinet, and the open sides of the mountings 27 against the inner faces of walls 13 and 14. In so positioning the mountings, the extensions 29 and 31 are inserted in the limited vertical passages 36 provided by the turned-in portions 21 and 22, whereby lateral movement of the forward portion of mountings 27, is prevented. A similar structure, or other suitable means, may be employed in the rear of the cabinet.

After the first pair of mountings 27 has been thus positioned, a shelf 35 is placed thereon, resting upon the upper ledges 32 of the oppositely disposed mountings. Thereafter, a second pair of mountings is operatively disposed upon the positioned shelf, and a second shelf placed upon the second pair of mountings, and in similar 105 110 fashion until the cabinet is complete. The

turned-in extensions 30 prevent the ledge 32 and bottom 34 from bending inwardly of the mountings 27 after pressure is exerted thereon. Moreover, the interfitting relation of ledges 32 and 33 with extension 30 prohibits any outward bending or sagging of front wall 37 of the mountings 27.

At this point it may be generally explained that the tray 38 is slidably held by the guide 39, and that guide 39 has a limited sliding movement on a shelf 35. Guide 39 has lugs extending outwardly therefrom. These lugs move upon the ledges 33 of the mountings 27, and contact the portions 21 and 22 of the cabinet thus limiting forward movement of the guide 39 but permitting projection of the front of the guide from the cabinet in the fully drawn position of the trays. Means are likewise provided, upon full inward movement of the trays, for moving the guides inwardly behind the fronts of the trays and cabinet to permit operation of the locking means, as will be explained.

The locking means of the present invention may be used on both sides of a cabinet, though its use on one side is generally sufficient. It is explained herein as used only upon the right hand side of the cabinet. Lock members 40, attached to the sides of tray 38 adjacent the front thereof, are preferably integral extensions of the front end 41 of the tray. Members 40 consist of shaped strips providing the notches or inwardly-extending depressions 42. The ends 43 of members 40 are attached to the exterior of the sides of tray 38. When tray 38 is moved into the cabinet, to its full extent, notches 42 come immediately adjacent and in direct alignment with the channels 23 and 24. Lock rod 44 of the locking means is a flattened rod, or one which is substantially rectangular in cross section. Rod 44 is positioned in channel 23 and is pivotally movable therein on a vertical eccentric axis. The off-center pintle 45 projects from one end of rod 44. The locking cam 46 projects from the other end of rod 44, the pintle 47 of cam 46 being in alignment with pintle 45. The stud 48 of cam 46 has perforation 49 adjacent its end.

Pintle 45 is pivotally received in the bearing 50 which is secured to cabinet 12 directly above channel 23. The perforation 51 in the bottom 16 pivotally receives pintle 47 but will not permit passage of the main body of rod 44 therethrough. A lock mechanism 52 extends through base panel 25 adjacent the right hand side thereof. On the inner face of panel 25 is secured the support bracket 53 through which lock mechanism 52 extends. A plate 54 is secured to the rear of lock barrel 55 and turns as the key turns the barrel, as is common in various barrel and tumbler locks. Adjacent the periphery of plate 54 is a pin 56 pivotally receiving one end of a connecting link 57. A perforation in the opposite end of link 57 pivotally receives the stud 48 of cam 46. A pin 58 passing through perforation 49 prevents separation of stud 48 and link 57. Connecting link 57 is given a 90 degree twist intermediate its ends so that one face of the link will be vertically disposed to co-operate with plate 54, and another

face thereof will be horizontally disposed to receive the vertical stud 48.

The operation of the lock is as follows: after trays 38 have been pushed into the cabinet, lock mechanism 52 is actuated by means of a key. Plate 54 turns and the link 57 pivotally attached thereto, moves with it. Link 57 actuates the cam 46 and rod 44 is pivotally actuated thereby, so that the lock rod 44 turns from the position shown in Fig. 3 and in solid lies in Fig. 4 to the position indicated by dotted lines in Fig. 4. Rod 44, being so actuated, moves into notch 42 and abuts the walls thereof, whereby movement of the trays is prevented until the rod is returned to its former position in channel 23, that is, until the cabinet is unlocked.

After the locking means have been completely installed, the elements positioned beneath the raised bottom 16 may be suitable enclosed for protection against tampering, and possible contact with other objects.

It is evident that this locking means is adapted for use with all sizes of cabinets; that it is equally effective in locking both trays and drawers, inasmuch as the element 40 can be easily applied to both.

What is claimed is:

1. The combination with a cabinet and trays adapted each for movement within a removable guide in the cabinet, the front of said guide being adapted to be moved outwardly of the front of the cabinet by withdrawal of the trays, of tray locking means comprising notched members attached to each tray and projecting laterally of the front thereof, a vertically extending channel portion at the front of the cabinet and adapted to register with the notches of said notched members in the enclosed position of the trays, a rod journaled in said channel portion, means operative upon full inward movement of the trays for moving said guides inwardly behind the fronts of the trays and cabinet to permit registration of said notches and channel, and means adapted to be operated after such inward movement of the guides for turning said rod on a vertical axis into and out of said notches for locking and unlocking the trays in the cabinet.

2. In combination, a cabinet, a guide in the cabinet, a tray in the guide, the front of the guide being adapted to be moved outwardly of the cabinet by withdrawal of the tray, tray locking means comprising a notched member on each tray and projecting laterally of the front thereof, a vertically extending channel portion at the front of the cabinet and adapted to register with the notch of said notched member in the enclosed position of the tray, a rod journaled in said channel portion, means operative upon full inward movement of the tray for moving the guide inwardly behind the fronts of the tray and guide to permit registration of said notch and channel, and means adapted to be operated after such inward movement of the guide for turning said rod on a vertical eccentric axis into and out of said notch for locking and unlocking the tray in the cabinet.

STANLEY B. FREIBERG.
